UNITED STATES PATENT OFFICE.

JAMES L. COOMBS, OF BANGOR, MAINE.

MOCCASIN-BOOT.

SPECIFICATION forming part of Letters Patent No. 251,837, dated January 3, 1882.

Application filed November 15, 1881. (No model.)

To all whom it may concern:

Be it known that I, JAMES L. COOMBS, of Bangor, in the county of Penobscot and State of Maine, have invented certain new and useful Improvements in Moccasin-Boots; and I do hereby declare that the following is a full, clear, and exact description of the invention, that will enable others skilled in the art to which it appertains to make and use the same, reference being had to the accompanying drawings, forming a part of this specification, in which—

Figure 1 shows a side elevation of my invention; Fig. 2, pattern of leg; Fig. 3, pattern of tip or tongue.

15 Same letters show like parts.

My invention relates to an improvement in moccasin-boots, and is designed to enable an improved article to be produced at a less cost than heretofore.

20 It consists in certain changes in the cut of the leg and tip or tongue, whereby the more valuable portions of the stock can be cut to greater advantage and the parts when united by any known seam take the form required for 25 the boot without crimping or any peculiar manipulation whatever.

It further consists in a peculiar method of uniting and forming the front seam, hereinafter mentioned, forming smooth work upon the 30 inside of the boot.

Reference to the drawings will explain my invention fully.

At *a* is the leg of a moccasin-boot, having its corners *b* removed, as shown.

35 At *c* is the tongue or tip, formed in two parts, *c' c'*, (see dotted lines, Fig. 2,) cut substantially as shown in Fig. 3, and united to the leg by a seam, *d*. This is best shown by the dotted lines in Fig. 2. The leg, with the attached tip-pieces, 40 is then folded upon the line *xx* and the edges of both leg and tip-pieces united by a continuous seam, *e*, extending from the top of the boot to the toe down the front. The bottom, which may be of the ordinary pattern, (and

hence not shown,) may now be attached in the 45 usual way.

As before stated, any known seam may be used; but for the seam *e*, I prefer (but do not claim as my invention) that the edges be first united loosely if hand-sewing be used, and 50 with a slack tension if stitched by a machine, and subsequently covered by a stay-piece, (see detail *f*.) This loose stitching permits the adjoining edges to "butt" instead of lapping when the boot is worn, making smooth work 55 on the inside, while the stay-piece, with its two additional lines of stitches, prevents any leakage and gives additional strength to the seam. If what is known as the "butting" seam is employed at first, less attention is required in regard to its looseness; but this is a hand-seam.

The form of the tip-pieces *c' c'*, as regards the sides *g h*, may be varied to a considerable extent in the manner shown by the dotted lines, Figs. 1 and 3; but the closer the pattern Fig. 3 65 is adhered to the more economically the hide will be cut.

The form of the leg having its corners *b* removed, as shown, enables the stock to be cut to much better advantage than when the corner 70 is a right angle.

It will be understood, of course, that the leg may in certain cases, when it is necessary to save stock, be cut in two pieces instead of one, as this is a common expedient.

75 What I claim as my invention is—

A moccasin-boot pack having its leg and tip or tongue cut substantially from the pattern shown and described, and united by the seams *d e*, said seams being of any known character. 80

In testimony that I claim the foregoing I have hereunto set my hand this 12th day of November, 1881.

JAMES L. COOMBS.
